UNITED STATES PATENT OFFICE.

RALPH B. PURINTON AND CLAUDE W. PLACE, OF CHICAGO, ILLINOIS, ASSIGNEES TO
GENERAL ELECTRIC COMPANY, A CORPORATION OF NEW YORK.

ELECTRIC GENERATING SYSTEM.

Application filed May 22, 1923. Serial No. 640,705.

To all whom it may concern:

Be it known that we, RALPH B. PURINTON and CLAUDE W. PLACE, citizens of the United States, residing at Chicago, in the county of 5 Cook, State of Illinois, have invented certain new and useful Improvements in Electric Generating Systems, of which the following is a specification.

Our invention relates to electric generating systems and while applicable to manually or automatically controlled generating plants is of particular use in automatic hydro-electric generating plants. An object of our invention is to provide in such a system 10 for maintaining closed during a momentary reduction or failure in the line voltage the main switch by which the generator or generators are connected to the line. Another object is to provide for the 15 opening of the switch after a failure of the line voltage shall have continued for a predetermined length of time or to provide for opening the switch in the event that such failure in voltage or a reduction of the same 20 below a predetermined value recurs at too frequent intervals. A further object is the provision of a source of energy which shall be always available for opening the main switch after the line voltage has completely 25 failed.

Our invention will be better understood by reference to the accompanying specification and drawing and its scope will be pointed out in the appended claims.

35 Fig. 1 is a cross section of a cell showing an oil switch therein and a part of the operating mechanism therefor, the switch being shown in its closed position; Fig. 2 is a cross sectional view taken on the line 2—2 40 and looking in the direction of the arrows, and Fig. 3 is a circuit diagram, the various switches being shown in open circuit position.

45 Referring now to the drawing, an oil switch denoted generally by reference number 1 is shown enclosed by a cell 2 upon which is mounted the main operating lever 3 connected to the switch by the operating rod 4 and operated by the toggle links 5 and rod 6. Rod 6 is pivoted to lever 7 which lever is held in the position illus-

trated by Fig. 1, which corresponds to closed circuit position of the switch, by means of two sets of toggle links 8 and 9. This construction thus far described is that in common use in solenoid operated oil switches and forms no part of our invention.

In the automatic hydro-electric generating plant to which our invention is shown applied, a source of oil pressure (not shown) 55 is provided which in addition to operating a governor (not shown) for the water wheel also provides the operating force for closing the main switch and for controlling the tripping open of the same. Referring now to Fig. 2, the frame 11 has depending therefrom a spacer 12 to which is attached a cylinder 13 in which slides a piston 14 carrying a piston rod 15. The piston rod 15 in ascending engages the lever 7 to rotate it in a clockwise direction, thereby lifting the rod 4 to close the main switch. A coil spring 16 insures the return of the piston 14 to its normal position. The toggle links 9 may be caused to buckle and thereby to trip open 65 the main switch either by the energization of the usual trip solenoid 17 operating through the rod 18 or by an oil controlled device now to be described. This device 70 comprises a cylinder 20 having walls integral with the spacer 12, through which cylinder slides a piston 21 carrying a piston rod 22. The rod 22 engages rod 18 and slides through a head 23 closing the upper end of the cylinder. A coil spring 24 arranged in the cylinder 20 operates to raise 75 the piston 21 and rod 22 to trip open the main switch. A small passage 25 is shown connecting the cylinders 20 and 13 whereby any oil that passes the piston 21 may escape 80 into the larger cylinder and this oil together with any oil that passes the piston 14 may escape through the passage 26 into pipe 27. For controlling the admission of oil 85 into the cylinder 13 and its exit therefrom an electro-magnetically controlled valve is provided. For this valve a pair of spaced valve seats is formed on a lateral extension 29 of the cylinder 13 and the space between the two seats is connected by a passage 30 90 with the cylinder 13. A frame member 31 mounted upon the lateral extension 29 has

95 100

its lower portion forming a cylinder in which a piston 32 slides somewhat loosely. A valve 33 is formed on the lower end of this piston to engage the upper valve seat, 5 the piston being reduced in diameter immediately above the valve to form an annular space with which the inlet passage 34 connects. A second valve 35 supported from the piston 32 by a rod 36 cooperates with 10 the lower valve seat to control the escape of oil from the cylinder 13 into the exhaust pipe 37 and thence to the sump. Mounted on the top of the member 31 is an electromagnet comprising a solenoid 39 and a plunger 40, 15 at the lower end of which is a weight 41. A valve rod 42 sliding in an intermediate portion of the frame member 31 supports the plunger 40 and weight 41 and has a valve 43 at its lower end which controls a passage 20 leading from space above the plunger 32 to a pipe 44 connecting with the exhaust pipe 37. A compression spring 45 is arranged above the plunger 32 to urge the same down against the oil pressure. The piston 25 21 is normally depressed by oil pressure admitted through pipe 53 so that the spring 24 is held compressed. Any oil that escapes past the head 23 may find its way back into the cylinder 13 through a small opening 46 and 30 the opening for the piston rod 15. A switch 48 shown diagrammatically in Fig. 3 as a back contact on the main switch 1 is mounted on the frame 12 to be operated by lever 7 and is connected in series with the solenoid 39. It serves to hold this solenoid open 35 circuited while the main switch is closed.

The valves controlled by the solenoid 39 admit oil to and release it from the cylinder 13 but for varying the pressure in the cylinder 20, whereby under proper conditions the main switch 1 may be tripped out, an additional solenoid operated valve, commonly termed a cut-off valve, is employed which will now be described. This valve as a whole 40 is similar in construction to that just described with the exception that it has a single seat with which the valve 50 cooperates to control the flow of oil from the pipe 51, leading from an oil pressure tank, to the pipe 52. From pipe 52 one branch pipe 53 leads to cylinder 20 and to the valve 33 while another branch 54 leads to a governor (not shown) such as that commonly used in systems of this type. The present valve like 45 that previously described has a casing or frame 55 forming a seat for the valve 50 and has a cylindrical portion in which a piston 56 fits somewhat loosely, being urged down by a spring 57. A valve 58 controls the flow of oil from the cylindrical portion of the casing to a pipe 59 connecting with the sump through pipe 37. Resting upon the valve stem of this valve 58 is a plunger 68 carrying a weight 60, the plunger and weight being 50 adapted to be lifted by a solenoid 61.

In the normal operation of the plant, the solenoid 61 remains energized thereby permitting the oil pressure to hold open valves 58 and 50. While the construction and operation of the valves 33 and 50 together with 55 the mechanism for controlling the same have necessarily been described in detail, the specific construction of these valves and their respective controlling mechanisms form no part of the present invention.

In Fig. 3 we have shown a circuit diagram which illustrates a very simple manner of connecting the above described apparatus. For convenience the apparatus is shown connected to a single phase transmission line comprising conductors A and B and, for the sake of simplicity, connections are made directly therewith without the use of the usual transformers. The single switch 64 may be considered as representative of a number of switches severally responsive to various conditions affecting the operation of an automatic hydro-electric station, such for example as the temperature of the bearings, the strength of the generator field current, the level of water in the forebay, etc. A switch 65 will be closed when the generator has reached nearly synchronous speed. This switch may be a centrifugal switch set to close when the generator speed reaches 95% of synchronous speed. The latch device shown at 66 represents diagrammatically the toggles 8 and 9 by which the main switch 1 is held closed connecting the generator G to the line but which may be tripped open either by the solenoid 17 in response to an overload when switch 67 is closed or by the raising of the piston 21 in response to a predetermined reduction in oil pressure.

The operation of the above-described apparatus is in part as follows: Assuming the plant to be in normal operation and to be delivering energy to the line, the various switches represented as a whole by switch 64 will be closed and the solenoid 61 accordingly energized. Valve 58 being allowed to open, oil under pressure from the pressure tank holds the piston 56 raised and valve 50 open, whereby oil is supplied to the governor, to the cylinder 20 and to valve 33. A certain amount of oil constantly escapes past the piston 56 back to the sump and likewise a certain amount escapes through the governor. The main switch 1 being closed, the solenoid 39 is open circuited by the switch 48 so that valve 43 remains closed. The escape of oil which leaks past the plunger 32 being thereby cut off, the combined oil and spring pressure on the top of the plunger causes the valve 33 to remain closed. Due to the connection of the cylinder 20 with the pipe 52 the pressure of oil in this cylinder maintains the piston 21 depressed compressing the spring 24. Should now a momentary reduction occur in the line 100 105 110 115 120 125 130

voltage, sometimes termed a dip in the voltage, as might result for example from the throwing in of a heavy load or from a lightning discharge, the valve 58 controlled by 5 the solenoid 61 may momentarily close. However, before the valve 50 will close a certain quantity of oil must leak past the plunger 56. Moreover, after the valve 50 has seated, pressure in the pipe 52 and connecting pipes will be reduced only to the extent that the oil escapes through the governor. A certain amount of time is therefore required after the controlling solenoid 61 has permitted the valve 58 to close before 10 the oil pressure in the cylinder 20 will be sufficiently reduced to cause the rod 18 to trip open the main switch. It is to be noted that the force for actuating the trip in this case is that furnished by the coil spring 24 15 which previously had been compressed and so maintained by the oil pressure. It will therefore be evident that even though the line voltage should fail completely and should the water wheel be shut down there 20 is always a reliable source of energy available for tripping out the main switch.

The apparatus devised by us is of particular value in the event that the line voltage is at the critical value when the automatic station is thrown on the line in starting. As stated in the description above, the centrifugal switch which controls the switch 30 65 is usually set to cause the generator to be thrown on the line when the speed is approximately 95% of synchronous speed. Where electromagnet devices responsive to line voltage are employed to trip out the main switch, a hunting or pumping action often follows due to the repeated tripping 35 out of the main switch resulting from the additional line drop produced each time the generator is thrown on the line. The trip controlling mechanism which we have disclosed herein, however, permits the generator 40 45 to remain on the line sufficiently long to be brought up to full synchronous speed and to supply energy thereto.

Should the reduction or failure of line voltage occur intermittently such as might 50 result from a swinging short circuit the repeated reduction in oil pressure will, after it has continued for a reasonable length of time, become sufficient to cause a tripping out of the main switch, however, if the cause 55 of the trouble is removed and the line voltage resumes its normal steady value before that time no tripping of the switch will occur.

In starting the automatic station, the closing of the switch 65 which as stated above, 60 may be speed controlled, energizes the solenoid 39 to open valve 43. The pressure of oil then lifts the piston 32 opening the valve 33 and closing valve 35. The piston 65 14 raises and through the levers, rods and

links shown in Fig. 1 closes the main switch 1. As the switch closes it opens switch 48 thereby deenergizing solenoid 39 and valve 43 closes. Spring 45 together with the oil that leaks past the piston 32 now moves 70 valve 33 to closed position and opens the exhaust valve 35 to permit the return of piston 14.

While we have described only one embodiment of our invention, we do not wish 75 to be limited to the particular form shown and described as it will be apparent that many modifications therein may be made without departing from the scope of our invention as set forth in the appended claims. 80

What we claim as new and desire to secure by Letters Patent of the United States, is:

1. In a system comprising a generator, a line adapted to be supplied thereby and a switch for controlling the connection between said generator and line, fluid pressure controlled mechanism responsive to a failure in the line voltage for tripping open said switch, and a normally stressed resilient member for actuating said mechanism. 85

2. In a system comprising a generator, a line adapted to be supplied thereby and a switch for controlling the connection between said generator and line, fluid pressure controlled means for tripping open said switch, and means responsive to a predetermined reduction in line voltage for varying said fluid pressure. 90

3. In a system comprising a generator, a line adapted to be supplied thereby and a switch for controlling the connection between said generator and line, a trip for said switch, a resilient member for actuating said trip, fluid pressure means for restraining the operation of said resilient member, and means responsive to the voltage condition of said line for releasing said fluid pressure at a predetermined rate. 100

4. In a system comprising a generator, a line adapted to be supplied thereby and a switch for controlling the connection between said generator and line, fluid pressure controlled means for tripping said switch upon a predetermined reduction in pressure of said fluid, and means responsive to a temporary drop in the voltage of said line for causing a delayed reduction in said pressure followed by a subsequent restoration of said pressure. 115

5. In a system comprising a generator, a line adapted to be supplied thereby and a switch for controlling the connection between said generator and line, a spring operated trip for said switch, fluid pressure means for preventing the operation of said trip, means comprising a valve for slowly reducing the pressure of said fluid, and an electromagnet responsive to the line voltage for controlling said valve. 125 130

6. In a system of the character described, a main switch, fluid operated actuating means therefor, a source of fluid pressure, a valve for admitting fluid pressure therefrom to said actuating means, electromagnetic means for controlling said valve, and a switch responsive to the closing movement

of said main switch for opening the circuit of said electromagnetic means.

In witness whereof, we have hereunto set our hands this 19th day of May, 1923.

RALPH B. PURINTON.
CLAUDE W. PLACE.
